TOY RICKSHAW

Wendell J. Nagy, 19007 Longview Ave.,
Maple Heights, Ohio

Filed Jan. 22, 1962, Ser. No. 68,406

Term of patent 14 years

(Cl. D34—15)

FIG. 1 is a side elevation of a toy rickshaw showing my new design;

FIG. 2 is a front view of the toy rickshaw;

FIG. 3 is a rear view of the toy rickshaw;

FIG. 4 is a top plan view of the toy rickshaw, and FIG. 5 is a bottom plan view of the toy rickshaw.

The dominant features of my design reside in the portion shown in full lines, with the broken line showing of wheels omitted in FIG. 1 for convenience of illustration.

The characteristic features of my design reside in a toy rickshaw including a supporting chair contoured of smooth flowing lines having a foot rest portion extending therefrom, a bracket portion extending from the chair for supporting wheels thereon with a pair of thin cylindrical

easel-like legs extending from the bracket portion in the rear of the chair, and a pair of elongated handle members extending linearly outwardly on either side of the chair.

The side opposite to that shown in FIG. 1 is the same as that shown in FIG. 1.

I claim:

The ornamental design for a toy rickshaw, substantially as shown and described.
